GROUP AUDIPHONE SYSTEM

Sterling G. Sears, Garden City, N. Y., assignor to
 Dictograph Products Company, Inc., New York,
 N. Y., a corporation of Delaware

Application October 11, 1935, Serial No. 44,515

6 Claims. (Cl. 179—1)

This invention relates to a group audiphone system and has particular reference to a plurality of individual hearing aid devices responsive to a common remote sound transmitting source and especially adapted for aiding the hard-of-hearing among the audience of a theater, the congregation of a church, the assembly of a convention, or any other gathering or groups of persons to clearly hear the entertainment, services, or proceedings, with comfort and convenience.

Inasmuch as it is obviously impracticable to provide a hearing aid device for each seat in a theater, church, or the like, and is impossible to properly distribute a number of such devices to the relatively few deaf persons for actuation from a common source of sound, such as the speaker's or actors' microphone, the sound reproducing apparatus of a talking picture machine, or the like, the arrangement heretofore has been to provide each seat with a connection box with which a portable hearing aid receiver may be connected by the individual user, the connection boxes being connected in series or parallel with the transmitting microphone and amplifier, talking picture machine, or other source of sound in which the hearer is interested. However, because these individual receivers are usually not connected in the transmission circuit at the same time, the intermittent connection and disconnection of the several receivers by the users creates an almost continually varying load on the system during certain periods, with the result that the reception of the sound by the several users varies, causing frequent adjustment of their individual volume-control rheostats with consequent diversion of attention, nuisance and discomfort.

In accordance with the present invention, a group audiphone system is provided, which may be either temporarily or permanently installed in a theater, church or other auditorium or gathering place with ease and rapidity, which is so arranged that the distribution of the individual receivers may be varied at will according to the number and location of the persons requiring them, which is adjustable in accordance with the distance of the source of sound from the microphone and requires no further adjustment, and with which the transmission of the sound remains uniform, clear and undisturbed, no matter how many of the individual or groups of receivers are connected into or out of the circuit during the period of transmission of the sounds.

More particularly, the invention comprises an amplifier provided with a volume control variably calibrated to the distance of the source of sound

from the microphone and having a resistance or impedance connected across its output terminals, which is substantially equal to the resistance or impedance of the maximum number of individual receivers, and which is disconnected when the load, which is substantially equal to the maximum number of individual receivers, is connected thereto.

This substitute load is represented by complementary resistances or impedances preferably connected in series and located in junction or jack boxes connected by a main cable for distribution at properly located central points throughout the auditorium, the number of such resistances or impedances equaling the number of sub-distributing connections required, and aggregating a resistance or impedance substantially equal to the substitute load resistance or impedance in the amplifier and consequently substantially equal to the load of the maximum number of individual receivers.

Each of these sub-distributing connection box resistances or impedances is substantially equal to the total resistance or impedance of the corresponding bank of individual receivers allotted to that junction box and is disconnected when this bank is connected to the box. There are corresponding jack boxes for receivers, and each of them is provided with a resistance or impedance substantially equal to the resistance of the corresponding receiver and disconnected when that receiver is plugged in.

These substitute resistances or impedances for the receivers are preferably connected in parallel, so that the entire distribution system is connected in series-parallel, and the several substitute loads for the individual receivers, each group or bank of receivers and of the entire distribution system are complementary and correlated in such a way that the amplifier is serving a full load at all times, regardless of the number of receivers in service at any one time and the volume and quality of the sound are unaffected and the reception is undisturbed by clicks or contact noises due to connection or disconnection of one or more receivers in the system during the period of the sound transmission. This series-parallel arrangement also protects the system and apparatus against injury as the result of short-circuiting of a jack, for example by an extraneous conductor inserted therein, a short-circuited receiver cord, or sub-distribution cable, or the like. Also, broken or otherwise open receiver cords or the like, are prevented from affecting the system in a detrimental way.

The receiver jack boxes for temporary or portable installations comprise housings provided with a clamp or hook whereby they may be supported on or by the rear of the chair or seat in front of the user and are connected to the redistributing cable. Each of these portable jack boxes contains the substitute load resistance for the corresponding individual receiver, and is fitted with a jack for receiving the plug of the receiver, which is suspended from a hook on the jack box when not in use. A flat plug having little lateral projection is provided and the cord connecting the receiver thereto is preferably fitted with a volume control rheostat. For permanent installations such as for theaters, in which the amplifier is connected directly to the sound-reproducing apparatus of the talking picture machine, the receiver jack boxes are preferably secured to the underside of every other arm and are provided with double jacks, one for each adjoining seat.

It will be seen that with the group audiphone arrangement of this invention, a very simple, fool-proof and effective system of sound distribution for the hard-of-hearing is provided, which may be readily installed and operated with a minimum of labor and with a maximum of effectiveness and satisfaction to the users. Further advantages of the invention will become apparent upon examination of the accompanying drawings, in which:

Figure 1 illustrates the manner in which the group audiphone system of this invention may be installed;

Fig. 2 is a distribution wiring diagram of the same;

Fig. 3 is an enlarged perspective view of one of the portable jack boxes;

Fig. 4 is a distribution wiring diagram for a theater; and

Fig. 5 is an enlarged view of the amplifier range adjustment dial.

Referring to Fig. 1 of these drawings, numeral 10 designates a microphone located on a stage or 45 rostrum 11 or the like and connected by a cable 11 to an amplifier 12, which is energized from a suitable source of power connected thereto by cable 13 and which is provided with a jack adapted to receive the plug 14 connected to the main distribution cable 15. In a temporary installation 50 this distribution cable is laid along the floor, such as along the aisle of the theater or the like, and is provided at spaced intervals with jack boxes 16, the number of which depends upon requirements, 55 such as the number of tiers of seats or chairs to be served.

Jack boxes 16 preferably have two jacks to which are connectible by suitable plugs 17 the subdistribution cables 18 leading to a plurality 60 of individual jack boxes 19 preferably supported on the seats or chairs immediately in front of the position where the hearers sit, as is indicated in Fig. 3. These individual jack boxes 19 are each provided with a spring hook or clamp 20 adapted 65 to support the box on the back of the chair, and a hook 21 or the like on its underside upon which the headband 22 of the audiphone receiver 23 may be conveniently suspended when the receiver is not in use.

The audiphone receiver 23 may be of the conventional air conduction type or may be of the bone conduction type, as is illustrated, and adapted to be held against the bone structure of the user, such as on the mastoid eminence behind 75 the ear, by means of the headband 22. The elec-

tric cord 24 leading from the receiver 23 is fitted with a volume control rheostat 25 and with a flat plug 26 adapted to be inserted in the jack box 19. The head of the plug 26 is made flat, as illustrated, to project a minimum distance beyond the rear surface of jack box 19 so as not to catch on the clothing of persons passing through the aisle.

The arrangement illustrated is convenient and satisfactory for a temporary installation but if a permanent installation is required the cables 15 and 18 may be laid in conduits in the floor or the like, the amplifier 13 concealed and the microphone 10 located at suitable points, such as at 10'.

As is illustrated in the wiring diagram of Fig. 2, the output terminals 27 of the amplifier 13 are bridged by a resistance 28, which is substantially equal to the predetermined full load of the group audiphone system, so that, whether or not the plug 14 of the main distribution cable 15 is plugged into the jack 29, the load on the amplifier 12 is constant. The contact spring 30 of the jack 29 when engaged by the tip 31 of the plug 14 is moved out of engagement with the contact 32, to which one end of the resistance 28 is connected, so that the latter is disconnected from the output circuit of the amplifier 12. Simultaneously, the engagement of the tip and sleeve of the plug with the contact spring 30 and sleeve of jack 29 connects the main distribution cable 15 into the amplifier output circuit. Withdrawal of the plug 14 releases contact spring 30 so that it reengages contact 32 and reconnects resistance 28 across the output terminals 27 of the amplifier 12.

By way of illustration, if the plan of the auditorium requires as many as ten subdistribution cables 18 in order to secure proper distribution of the individual audiphone receivers 23, ten resistances 32 are preferably connected in series in the main distribution cable 15, each of these resistances being substantially equal to the full load of the corresponding subdistribution cable 18 and all of them aggregating a total resistance 45 which is substantially equal to the resistance of resistance 28 in the amplifier. For example, if the total predetermined load on the amplifier is 100 ohms the resistance of each individual resistance 32 is ten ohms.

In the arrangement illustrated in Figs. 1 and 2, two of such resistances are placed in each subdistribution jack box 16, one for each of the two jacks 33, which are adapted to receive the plug 17 of the corresponding subdistribution cable 18. The contact spring 34 of each of the jacks 33 normally maintains contacts 35 closed, but when plug 17 is inserted in jack 33, its tip 36, in engaging contact spring 34, causes the latter to break contacts 35, disconnecting the resistance 32. Contact spring 34 is connected to the corresponding wire of main distribution cable 15 on one side of resistance 32 and the sleeve of the jack 33 is connected to the opposite side of the resistance 32, so that the insertion of plug 17 effects connection of the subdistribution cable 18 to the main distribution cable 15.

The plurality of individual jack boxes 19 of subdistribution cable 18 each contain the jack 37 and a resistance 38, which is substantially equal 70 to the resistance of the audiphone receiver 23. The resistances 38 are connected in parallel in subdistribution cable 18 and are so arranged that their net resistance is substantially equal to the resistance of resistance 32. For example, if the

resistance of audiphone receiver 23 is 50 ohms and there are five individual jack boxes 19 for each subdistribution cable 18, the resistance 38 in each of them is substantially equal to 50 ohms, and since there are five individual jack boxes 19, the net resistance of the five resistances 38 is 10 ohms, according to the reciprocal rule regarding parallel resistances.

Each individual resistance 38 is preferably connected at one end to one of the wires of the subdistribution cable 18 and at the other end to contacts 39 normally closed by contact spring 40 of the jack 37, which is connected to the other wire of the subdistribution cable 18. When the plug 26 of the audiphone receiver 23 is plugged into jack 37 the tip of the plug causes contact spring 40 to disengage contact 39, thereby disconnecting resistance 38.

In operation, each of the elements of the group audiphone system of this invention is represented by a substitute load, so that the system is under full load at all times, no matter how few or how many of the individual audiphone receivers 23 are in use and no matter how few or how many of the subdistribution cables 18 are in use. Thus, the main distribution cable 15 may be laid and, as each of the subdistribution cables is connected by its plug 17 to the corresponding jack box 19, the resistance 32 corresponding to the subdistribution cable, is disconnected and substituted by the net resistance of the individual resistances 38, which is substantially equal to resistance 32. Similarly, as each of the individual audiphone receivers 23 is plugged into a jack box 19, the resistance thereof is substituted for the resistance 38, which is disconnected but which is reconnected and becomes a substitute load for the audiphone receiver 23 when the latter is disconnected.

With this arrangement, there is no fluctuation in the load on the amplifier of the group audiphone system and none of the individual users is disturbed by clicks or a change in reception by the connection and disconnection of individual audiphones during the period of the sound transmission, so that transmission remains clear and uniform under all operating conditions. Also the present arrangement provides a very flexible and simple system which may be installed in many different ways to suit circumstances and requirements.

For permanent installations, and especially those in theaters or the like, where the amplifier 12 is directly connected to the sound reproducing apparatus of talking picture machine, or the like, the individual jack box installations may be more or less permanent and attached to the under side of every other arm of the seats. To that end the arrangement illustrated in Fig. 4 is utilized in which the jack boxes 39 are suitably secured to the under side of the seat arms and are provided with opposite jacks, one for each adjacent seat. The substitute load resistances 41 for the two corresponding audiphone receivers 23 are connected in series in the series-parallel arrangement of the subdistribution cable 18.

The sleeve of the jack 40' is connected by a wire 42 to one end of the corresponding resistance 41, and the contact spring 43 of the jack 40' normally closes contacts 44 connected to the other end of the resistance when the plug 26' of the audiphone receiver 23' is inserted in jack 40', its tip causes contact spring 43 to disengage contacts 44, disconnecting resistance 41 from the circuit. Conversely, when plug 26' is withdrawn, contact

43 is released to close contacts 44 to reintroduce substitute load resistances 41 into the distribution circuit. As shown in Figs. 3 and 4 the audiphone receivers 23 and 23' may be held by headbands 22, or by the handle 45, and a volume control rheostat 25 of the button type may be used or one of the slider type, such as indicated at 46 in Fig. 4, may be used.

The location of the source of sound from the microphone 10 or 10' normally determines the degree of amplification necessary for the audiphone system. Accordingly, the rheostat of the amplifier of this invention is calibrated to the distance of the source of sound from the microphone. For example, if the distance X of the speaker is ten feet from the microphone 10 in Fig. 1, rheostat 41 is adjusted so that its pointer 48 indicates 10 on the dial 49, which is subdivided into feet of microphone range, as is indicated in Fig. 5. This adjustment remains constant for all transmission purposes and need be varied only when the distance of the source of sound of the microphone 10 varies materially.

While several preferred embodiments of the invention have been illustrated and described herein, it is to be understood that the invention is not limited thereby, but is susceptible of changes in form and detail within its scope. The term "resistance" as used herein and in the appended claims is regarded for purposes of this application as synonymous with or comprehending an impedance.

I claim:

1. In a group audiphone system, the combination of a source of sound transmission, a main distribution line connected thereto and having a plurality of spaced resistances connected in series and having a total resistance substantially equal to the predetermined full load of the system, a plurality of subdistribution lines adapted to be connected individually across each of said resistances for disconnecting them, a plurality of spaced resistances connected in parallel in each subdistribution line and having a total resistance substantially equal to the corresponding resistance in the distributing line, and a plurality of audiphones each adapted to be connected across a subdistribution line resistance for disconnecting it and having a resistance substantially equal to said subdistribution line resistance, whereby the load on the source of sound transmission remains constant regardless of the connection and disconnection of the several subdistribution lines and audiphones in the main distribution line.

2. In a group audiphone system, the combination of a source of sound transmission, an amplifier therefor, a resistance across the output terminals of the amplifier and substantially equal to the predetermined full load of the system, a distribution line connectible across the output terminals of the amplifier for disconnecting the said resistance, a plurality of resistances in said distribution line substantially equal in total resistance to the said predetermined full load of the system; said resistances being connected in series, a plurality of subdistribution lines adapted to be connected individually across each of said resistances for disconnecting them, a plurality of spaced resistances connected in parallel in each subdistribution line and having a total resistance substantially equal to the corresponding resistance in the distributing line, and a plurality of audiphones each adapted to be connected across a subdistribution line resistance for disconnecting it and having a resistance substantially equal to

said subdistribution line resistance, whereby the load on the source of sound transmission remains constant regardless of the connection and disconnection of the several subdistribution lines and audiphones in the main distribution line.

5. 3. In a group audiphone system, the combination of a source of sound transmission, an amplifier connected thereto, a plurality of spaced jack boxes, a distribution cable connecting said boxes to the amplifier, a plurality of subdistribution cables, a plug for each of said subdistribution cables for connecting the latter to corresponding jack boxes, spaced jack boxes in each subdistribution cable, an amplifier for each subdistribution 10 jack box having a plug for connection with the latter, a resistance in each subdistribution cable jack box substantially equal to the resistance of the corresponding audiphone and adapted to be disconnected by the plug of the latter, a resistance in each distribution cable jack box substantially equal to the total resistance of the subdistribution cable and adapted to be disconnected by the plug of the latter, whereby the load on the system remains constant regardless of the connection and disconnection of the audiphones and 15 subdistribution cables in or out of the system.

20 25

4. In a group audiphone system for theaters

and the like, the combination of a source of sound, a remote jack box supported on alternate seats of a row, double jacks on the jack box connected in series to the source of sound, a resistance connected across the contacts of each 5 jack, and a normally-closed switch between one side of the resistance and one of the jack contacts adapted to be opened by a plug inserted in the jack.

5. In a group audiphone system, the combination of a microphone, an amplifier connected thereto, a rheostat in the amplifier circuit for controlling the output volume thereof, a dial for the rheostat divided in increments of distance of the source of sound from the microphone, and 10 15 a plurality of audiphones connected to the amplifier.

6. In a sound transmission system, the combination of a transmitter, an electrical sound amplifier connected thereto, a receiver connected to 20 the amplifier, an adjustable volume control for the amplifier, a pointer thereon, and a dial for the pointer divided in increments of distance of the transmitter from the source of the sound to be transmitted.
